UNITED STATES PATENT OFFICE

CARL BEER, OF CHICAGO, ILLINOIS.

IMPROVEMENT IN TOY POP-GUNS.

Specification forming part of Letters Patent No. **175,409**, dated March 28, 1876; application filed February 16, 1876.

To all whom it may concern:

Be it known that I, CARL BEER, of Chicago, in the county of Cook and State of Illinois, have invented a Toy Pop-Gun, of which the following is a specification:

My invention consists in the peculiar construction of a pop-gun and its plunger-handle, which is a hollow cylinder, having a whistle at the end, which is blown by the action of the piston on the end of the plunger each time the latter is moved.

Figure 1 is a perspective view of the pop-gun ready for firing. Fig. 2 is a vertical section of the same after firing.

In the drawing, A represents the barrel of the pop-gun, of which B is the plunger-rod, carrying a piston, a, fitting the bore of the barrel, and at the other end a larger piston, b, fitting the bore of a hollow handle, C, in the end of which there is a tin whistle, c. At the other end of the handle there is a diaphragm, d, to prevent the piston b from being drawn out. The dia-

phragm is also perforated with holes e for the free admission and emission of air. A cork, D, fastened by a cord, f, to the end of the barrel, is placed forcibly in the muzzle after the plunger is drawn back; then, as the latter is pushed in, the handle slides forward on its piston, expelling the air through the whistle, making a musical sound, followed by the expulsion of the cork with a sharp detonation. Upon retracting the plunger the whistle is again blown.

What I claim as my invention is—

The combination of the hollow handle C, having the whistle c, with the plunger B of a pop-gun, provided with the piston b, fitted to the bore of said handle, substantially as described.

CARL BEER.
